[57] **CLAIM**

The ornamental design for latching poultry cage gate, as shown and described.

DESCRIPTION

FIG. 1 is a top plan view of a latching poultry cage gate embodying my new design.

FIG. 2 is a bottom plan view thereof;

FIG. 3 is a front elevational view thereof;

FIG. 4 is a fragmentary cross sectional view taken on line 4—4 of FIG.1;

FIG. 5 is a fragmentary cross sectional view taken on line 5—5 of FIG.1;

FIG. 6 is a rear elevational view thereof; and

FIG. 7 is a side elevational view thereof, with a center portion omitted for convenience of illustration.

The fragmentary broken line representation of a poultry cage in FIGS. 1, 3 and 4 is for purposes of illustration only.

FIG.1

FIG.3

FIG. 6

FIG. 7

FIG. 2
